DESIGN FOR A TUMBLER AND BRUSH HOLDER

Harold Van Doren, Philadelphia, Pa., assignor to Gerity-Adrian Manufacturing Corporation, a corporation of Michigan

Application November 9, 1944, Serial No. 116,233

Term of patent 14 years

(Cl. D4—3)

To all whom it may concern:

Be it known that I, Harold Van Doren, a citizen of the United States, residing at Philadelphia, in the county of Philadelphia and State of Pennsylvania, have invented a new, original, and ornamental Design for a Tumbler and Brush Holder, of which the following is a specification, reference being had to the accompanying drawing, forming part thereof.

In the drawing:

I claim:

The ornamental design for a tumbler and brush holder, substantially as shown.

HAROLD VAN DOREN.
